RAILWAY CAR SPRINGS

Harry W. Frost, Jr., Detroit, Mich., and Louis E.
Endsley, Pittsburgh, Pa.

Application March 22, 1950, Serial No. 151,088

6 Claims. (Cl. 267—9)

1

Our invention relates to railway car springs such as are employed for supporting the ends of truck bolsters within the car truck side frames, and more particularly to those springs of the spring-group type wherein each group comprises a plurality of coil springs for supporting the truck bolster, each spring group being assembled as a unit and having a frictional snubbing device incorporated therewith to prevent excessive oscillations or vibratory movements.

One object of our invention is to provide a group-spring structure and snubbing device therefor of such form that the snubbing or frictional device can be inbuilt into the group-spring unit in a simpler manner than prior devices of this character, and wherein replacements of the snubbing or frictional elements can be made quickly and easily.

Another object of our invention is the provision of an improved means for placing the snubbing springs under the compression that is required for the desired friction.

Still another object of our invention is to provide for placing the snubbing springs under compression by a single tensioning element, but wherein each spring will be held in a compressed condition even though the other spring fails.

As shown in the accompanying drawing, Figure 1 is a view of a spring unit, partly in plan, and partly in section on the line I—I of Fig. 2; Fig. 2 is a view taken on the line II—II of Fig. 1; Fig. 3 is a side elevational view of the structure of Figs. 1 and 2; Fig. 4 is a side view of the top spring plate of Fig. 1 and its attached spring housings; Fig. 5 is an inner face view of one of the friction shoes of Fig. 2; Fig. 6 is an edge view thereof; Fig. 7 is an edge view of the spring compressing and tensioning element of Fig. 2, and Fig. 8 is a face view thereof.

It will be understood that a group spring unit as shown in the drawing will be employed in each car truck side frame to support the ends of the truck bolster and that the snubbing device will prevent accumulation of vertical oscillations or vibrations in the conventional load-carrying springs.

The unit includes four conventional load-carrying springs of the coil type indicated at 13, interposed between top and bottom plates or caps 11 and 12, the bottom plate or seat 12 being supported within the truck frame and a truck bolster extending crosswise of the plate 11, the plates being here shown as provided with the usual bosses or knobs 13 and 14 respectively, to center and hold the plates 11 and 12 against slipping or displacement relative to the bolster and truck frame.

2

The bottom plate or spring seat 12 has a casing 15 that extends upwardly and has end walls 16 to which wear plates 17 are welded, these plates being employed to serve as frictional surfaces and thus avoid rubbing of friction shoes directly on the end walls 16 of the casing.

The top plate 11 has a pair of spring housings 18 formed on its undersurface, for receiving a pair of snubbing springs 19. At their remote 10 sides, the housings have rectangular openings 20 to loosely receive shoes 21 that have frictional engagement with the friction plates 17.

The housings 18 have holes 22 through their partitions or inner walls, to loosely support the 15 inner ends of the springs 19, the outer ends of the springs being supported by bosses 23 that enter the end turns of the coils a slight distance. A spring seating block 25 of tapered form extends downwardly between the housings 18 and, when 20 pushed into place, will compress and hold the snubbing springs 19 under compression as shown in Fig. 2.

In service, the block 25 will move vertically as 25 a unit with the cap plate 11. The sloping faces of the block are "within the angle of friction" in that the block will not be ejected or moved upwardly simply through thrust of the springs 19. However, the bolster will usually rest on the upper end of the block 25 and hold it against upward movement. As shown in Fig. 2, the block 30 and adjacent wall of the top plate have holes therethrough to receive a pin 26 that may conveniently be used to hold the snubbing elements in assembled relation when there is no bolster on the spring group. Also, the pin, when partly 35 withdrawn as shown in Fig. 2, can serve as a convenient means for pulling the block 25 from the spring housings.

Clearance is provided at 27 between the outer 40 faces of the housing 18 and the shoes 21, to provide for lost-motion between the bolster and the truck frame when they have relatively swinging movement around a vertical axis and to thereby avoid binding or damage as between the upper and lower portions of the spring unit.

Another feature of our invention is the provision 45 of the arrangement whereby the snubbing elements can readily be placed and removed. In assembling the device, the top plate 11 will be held clear of the casing 16 to permit insertion of the snubbing springs 19 through the openings 20 and the placing of the shoes 21 in said openings. At this time, the springs 19 are not under any compression. The top portion of the unit 50 can then be slid into place between the friction plates 17. The block 25 will then be driven into position to place the springs 19 under compres-

sion against their respective shoes. To facilitate installation of the unit, in a truck frame and the placing of a bolster on the unit, the plates 11 and 12 will be compressed against the load-carrying springs 10 until holes 29 in the shoes 21 register with holes 30 and 31 in the casing walls 16 and the friction plates 17 respectively. Pins 32 can then be inserted into these holes to hold the parts in compressed position until installation in a car truck has been completed. Thereupon, the pins will be removed to permit normal functioning of the spring unit.

It is further to be noted that should one of the springs 19 break, the block 25 will still hold the other spring under compression.

We claim as our invention:

1. A spring group comprising top and bottom spring plates having load-carrying coils between them, an upwardly-extending casing on the bottom plate, downwardly-extending spring housings carried by the top plate and extending into the casing, friction surfaces on oppositely disposed walls of the casing, friction shoes extending slidably through oppositely-located walls of the housings and having engagement with said surfaces, a pair of coil snubbing springs, partition walls in the housings, having openings to loosely receive the inner ends of the pair of snubbing springs whose outer ends respectively seat against said shoes, and a spring-seating block removably inserted between said partitions and engaging the inner ends of the snubbing springs to compress them against the shoes.

2. A spring group comprising top and bottom spring plates having load-carrying coils between them, an upwardly-extending casing on the bottom plate, downwardly-extending spring housings carried by the top plate and extending into the casing, friction surfaces on oppositely disposed walls of the casing, friction shoes extending slidably through oppositely-located walls of the housings and having engagement with said surfaces, a pair of coil snubbing springs, partition walls in the housings, having openings to loosely receive the inner ends of the pair of snubbing springs whose outer ends respectively seat against said shoes, and a spring-seating block removably inserted between said partitions and engaging the inner ends of the snubbing springs to compress them against the shoes, the snubbing springs being generally horizontal but having their adjacent inner ends somewhat higher than their outer ends, to facilitate placing the block between them to compress the same.

3. A spring group comprising top and bottom spring plates having load-carrying coils between them, an upwardly-extending casing on the bottom plate, downwardly-extending spring housings carried by the top plate and extending into the casing, friction surfaces on oppositely disposed walls of the casing, friction shoes extending slidably through oppositely-located walls of the housings and having engagement with said surfaces, a pair of coil snubbing springs, partition walls in the housings, having openings to loosely receive the inner ends of the pair of snubbing springs whose outer ends respectively seat against said shoes, and a spring-seating block removably inserted between said partitions and engaging the inner ends of the snubbing springs to compress them against the shoes, the snubbing springs being generally horizontal and insertible into their housings, through the openings in the said oppo-

sitely-disposed walls that receive and support the friction shoes.

4. A spring group comprising top and bottom spring plates having load-carrying coils between them, an upwardly-extending casing on the bottom plate, downwardly-extending spring housings carried by the top plate and extending into the casing, friction surfaces on oppositely disposed walls of the casing, friction shoes extending slidably through oppositely-located walls of the housings and having engagement with said surfaces, a pair of coil snubbing springs, partition walls in the housings, having openings to loosely receive the inner ends of the pair of snubbing springs whose outer ends respectively seat against said shoes, and a spring-seating block removably inserted between said partitions and engaging the inner ends of the snubbing springs to compress them against the shoes, there being holes through said opposed walls and the shoes, in position for relative alinement when the load-carrying springs are compressed and to receive temporary holding pins that retain the unit in a partly-compressed condition, to facilitate handling and installation of the unit.

5. A spring group comprising top and bottom spring plates having load-carrying coils between them, oppositely disposed and upwardly-extending friction plates carried by the bottom plate, two pairs of downwardly-extending walls carried by the top plate and disposed between the friction plates, a friction shoe extending slidably through the outermost wall of each pair of walls and having rubbing engagement with the adjacent friction plate, a snubbing spring extending loosely through the inner wall of each of said pairs, in generally horizontal direction, and a wedge-shaped block removably inserted between the inner ends of the snubbing springs to hold them compressed against the said shoes.

6. A spring group comprising top and bottom spring plates having load-carrying coils between them, an upwardly-extending casing on the bottom plate, downwardly-extending spring housings carried by the top plate and extending into the casing, friction surfaces on oppositely disposed walls of the casing, friction shoes extending slidably through oppositely-located walls of the housings and having engagement with said surfaces, a pair of coil snubbing springs, partition walls in the housings, having openings to loosely receive the inner ends of the pair of snubbing springs whose outer ends respectively seat against said shoes, a spring-seating block removably inserted between said partitions and engaging the inner ends of the snubbing springs to compress them against the shoes, and a retaining member engageable with the upper follower and the block, to releasably retain the block in operative position.
